UNITED STATES PATENT OFFICE

108,227

DESIGN FOR A HEATER

Lawrence A. Althoff, Chicago, Ill.

Application June 25, 1937, Serial No. 70,060

Term of patent 7 years

To all whom it may concern:

Be it known that I, Lawrence A. Althoff, a citizen of the United States residing at Chicago, county of Cook, and State of Illinois, have invented a new, original, and ornamental Design for a Heater, of which the following is a specification, reference being had to the accompanying drawing, forming a part thereof, in which:

The figure is a perspective view of a heater, showing my new design.

Those of the sides of the heater which are not shown in the drawing are the same as those illustrated, except the rear wall opposite the door of the heater shown in the drawing and provided with the handle, this rear wall being plain.

I claim:

The ornamental design for a heater, as shown and described.

LAWRENCE A. ALTHOFF.
